TOE-IRON FOR SKI BINDING

Borje Hoffman, Langshyttan, Sweden, assignor to
Hoffmans Verkstads AB, Langshyttan, Sweden

Filed Oct. 25, 1974, Ser. No. 518,186

Term of patent 14 years

Int. Cl. D21—02

U.S. Cl. D34—14 D

FIG. 1

FIG. 2

FIG. 3

FIG. 4

FIG. 5

FIG. 6

FIG. 1 is a front perspective view of a toe-iron for a ski binding showing my new design;

FIG. 2 is a top plan view thereof;

FIG. 3 is a left side elevational view thereof;

FIG. 4 is a front elevational view thereof;

FIG. 5 is a bottom plan view thereof; and

FIG. 6 is a rear elevational view thereof.

I claim:

The ornamental design for a toe-iron for ski binding substantially as shown.
